FIG.1.

FIG. 2.

FIG. 3.

INVENTOR
FRANCIS C. HAMILTON

BY Frank Harrington
ATTORNEY

UNITED STATES PATENT OFFICE

109,320

DESIGN FOR A STATUETTE OR SIMILAR ARTICLE

Francis C. Hamilton, Evanston, Ill., assignor of one-half to L. Ray Schuessler, St. Louis, Mo.

Application January 24, 1938, Serial No. 74,494

Term of patent 7 years

To all whom it may concern:

Be it known that I, Francis C. Hamilton, a subject of the King of England, residing in Evanston, in the county of Cook, State of Illinois, having invented a new, original, and ornamental Design for a Statuette or Similar Article, of which the following is a specification, reference being had to the accompanying drawing forming a part thereof.

Fig. 1 is a plan view of the statuette or similar article embodying my new design.

Fig. 2 is a front elevation of the article illustrated in Fig. 1.

Fig. 3 is a side elevation of the article illustrated in Figs. 1 and 2.

I claim:

The ornamental design for a statuette or similar article, as shown.

FRANCIS C. HAMILTON.
